UNITED STATES PATENT OFFICE.

SAMUEL MOSBACHER, OF NEW YORK, ASSIGNOR OF ONE-HALF TO JAMES E. HILLS, OF BROOKLYN, AND FRANK E. WILLIAMS, OF NEW YORK, N. Y.

PORTABLE SHELF.

SPECIFICATION forming part of Letters Patent No. 471,697, dated March 29, 1892.

Application filed April 27, 1891. Serial No. 390,580. (No model.)

To all whom it may concern:

Be it known that I, SAMUEL MOSBACHER, a citizen of the United States, residing at New York, in the county of New York and State 5 of New York, have invented certain new and useful Improvements in Portable Shelves; and I do hereby declare the following to be a full, clear, and exact description of the invention, such as will enable others skilled in the 10 art to which it appertains to make and use the same.

My invention relates to portable shelves for display of goods of salesmen and for other purposes to which the same may be adapted; 15 and it consists of folding shelves, jointed uprights for same, and folding braces to steady the united parts, together with minor details of construction and arrangement, as will be more fully hereinafter set forth.

20 Heretofore it has been necessary for a traveling salesman to have shelves built at each town, city, or other place visited by him upon which to arrange his goods for the purposes of display, either at the hotels where sojourning 25 or in other localities, and after dispensing with the use of such shelves they ceased to be of service and were torn down or destroyed, and on reaching his next destination another set of shelves would have to be put up for the 30 same purpose. This caused a great loss of time, annoyance, and expense, as will be readily appreciated.

The object of this invention, therefore, is to provide portable shelves, especially for the 35 purpose set forth, having the parts thereof jointed and easily disconnectible from each other and adapted to be set up or taken down by the salesman at his several destinations and transported from place to place with his 40 luggage.

The object set forth is accomplished by the preferable form of device shown in the accompanying drawings, wherein similar letters of reference are used to indicate corresponding parts in the several views, and in 45 which—

Figure 1 represents a perspective view of portable shelves embodying the invention. Fig. 2 represents a similar view of some of the 50 parts partially disconnected. Fig. 3 represents a detail perspective view of the braces

in open and partially closed position. Fig. 3^a represents a detail perspective view of a part of the braces and one of the uprights, showing the manner of connecting said parts. Fig. 55 4 represents a detail perspective view of a part of one of the shelves. Fig. 5 represents a perspective view of a part of a modified form of shelf.

Referring to the drawings, A designates the 60 end uprights, consisting of two parallel vertical bars or rods made in sections adapted to be joined to each other with feet on the lower section and having cross connecting-rods B, with upwardly-projecting studs B' thereon. 65 The rear bar or rod of each of said uprights is provided with eyes B², respectively, at the upper and lower part of each section on the inner opposite sides thereof, for a purpose more fully hereinafter set forth. An intermediate upright C is located between the said end uprights A, and consists of two bars or rods D, which are each formed of two parts and connected by a hinge-joint, and the rear one of which is provided with an apertured ear D', projecting backward therefrom. The said bars or rods D have feet, and are also provided with connecting-supports either in the form of hooks D², alternately arranged, or horizontal studs D³, located at points to be 80 engaged by the joints of the shelves E, and thereby avoid interference with proper manipulation of said shelves in setting and taking down the parts of the device. The uprights are sustained in position by back-braces, 85 consisting of jointed bars F, having sleeves F' thereon to be slipped over the joints and preserve a rigidity of adjustment thereof when said bars are opened and mounted in position. The ends of said braces are provided with hooks F², which engage the eyes B² on the end uprights and broadened at their central portions, as at F³, and formed with slots F⁴ at an angle to each other and adapted to align when said broadened portions are 90 properly crossed and placed together for passage therethrough of the ear D'. A locking device F⁵ is disconnectibly carried by one of said braces, and is adapted to be inserted through the aperture of said ear D' against 100 the rearmost brace to hold said braces together.

The shelves E are shown in Figs. 1 and 2 with end and side frames and provided with a reticulated or open web E' to form supports. Said shelves are constructed in two parts 5 joined by hinges E², which are set back from the sides to permit the opposing joined ends of the parts to embrace the bars D of the uprights C and rest on the horizontal studs D³ or be engaged by the hooks D², as fully shown. 10 The ends of the shelves rest on the cross bars or rods B and the studs B' thereof engage the ends of the shelves inside of the end bars thereof to prevent longitudinal displacement. 15 By the use of the reticulated or open web E' dust and dirt are prevented from gathering and settling on the shelves, and lightness of structure combined with strength is attained.

In Fig. 5 a shelf is shown as made of solid 20 sections of wood or other material connected by hinges and formed with openings or eyes to engage the studs B' and the hooks D² of uprights A and C. This form of shelf lightens the construction and consequently the 25 weight in transportation. It will be observed that the hooks D² or studs D³ are arranged on opposite sides of the sections of the bars D, to which they are connected, in order that said sections may be readily folded without 30 interference of the parts.

In storing the device for transportation or other purpose the several parts are disconnected and folded and rendered compact in form, and, when desired, they can be readily 35 and quickly set up for use.

The device may be used for many purposes other than that set forth in households, stores, and offices.

Having thus described my invention, what 40 I claim as new, and desire to secure by Letters Patent, is—

1. In portable shelves, the combination of jointed uprights, folding braces connecting said uprights, and folding shelves, substantially as described.

2. In portable shelves, the combination of jointed uprights with shelf-supports, folding braces connecting said uprights, and folding shelves detachably connected to said uprights, substantially as described.

3. In portable shelves, the combination of jointed end uprights, intermediate folding uprights, and folding shelves supported by

said uprights and holding the said intermediate uprights in rigid position, substantially as described. 55

4. In portable shelves, the combination of end jointed uprights carrying studs, an intermediate folding upright carrying shelf-supporting devices, and folding shelves adapted to engage said studs and shelf-supporting devices, substantially as described.

5. In portable shelves, the combination of end jointed uprights having connecting cross bars or rods with studs, an intermediate folding upright with shelf-supporting devices, and folding shelves, substantially as described. 65

6. In portable shelves, the combination of jointed end and intermediate uprights, braces removably attached to said uprights, and shelves removably supported by said uprights, substantially as described.

7. In portable shelves, the combination, with end and intermediate uprights and removable shelves, of folding braces detachably connected to said uprights, substantially as described. 75

8. In portable shelves, the combination of end uprights, an intermediate upright having an apertured ear, removable shelves, crossed braces having their ends removably attached to said end uprights and formed with slots at their central portion to fit over said ear of the intermediate upright, and a detachable locking device carried by one of said braces to engage said ear, substantially as described.

9. In portable shelves, the combination of jointed end uprights having cross-bars with studs thereon and eyes at the rear portion thereof, an intermediate folding upright having shelf-supporting devices thereon and a rear apertured ear, folding shelves to engage said uprights, crossed braces having hooked ends to removably engage the eyes of the end uprights and slotted central portions to fit over the ear of the intermediate upright, and a pin disconnectibly carried by one of said braces to engage said ear, substantially as described. 95

In testimony whereof I affix my signature in presence of two witnesses.

SAMUEL MOSBACHER.
